[57] **CLAIM**

The ornamental design for a housing for brake mechanism for an industrial machine, as shown.

DESCRIPTION

FIG. 1 is a rear elevation view of a housing for brake mechanism for an industrial machine showing my new design;

FIG. 2 is a front elevation view thereof;

FIG. 3 is a side elevation view thereof;

FIG. 4 is a top plan view thereof;

FIG. 5 is an opposite side elevation view thereof;

FIG. 6 is a bottom, front perspective view thereof;

FIG. 7 is a perspective view of the front and one side thereof taken from below; and

FIG. 8 is a perspective view of the front and opposite side thereof taken from above.

FIG.1.

FIG.3.

FIG.2.

FIG. 4.

FIG. 5.

FIG. 6.
